ATTACHMENT FOR AIR BRAKE SYSTEMS

Robert K. Biery, New Orleans, La.

Application May 31, 1945, Serial No. 596,897

13 Claims. (Cl. 303—80)

1

This invention relates to an attachment for air brake systems, and more particularly to such an attachment adapted to be utilized in conjunction with air brake systems on railroad trains.

A primary object of this invention is the provision of means adapted to be actuated by the train line whereby the individual reservoir of each car may be exhausted by means of the train line.

As conducive to a clearer understanding of this invention it may be here pointed out that heretofore the train line has been utilized for filling the reservoirs of individual cars, and to apply and release the air brakes throughout the train. However, in exhausting the reservoir of the individual cars, it has been necessary to open the bleed valves thereof by hand for each individual car. By means of the instant invention the reservoirs of an entire train may be substantially simultaneously emptied in a desired period of time, the pressure in the train line being utilized to accomplish the automatic opening of the bleed valves.

An additional object of the invention is the provision of means adapted automatically to render the device of the instant invention inoperative when the train is going up or down incline, which inclination of the device would normally be operative to effect the operation thereof.

A further and more specific object of the invention is the provision of means in association with the means mentioned in the preceding object for precluding the operation of the means rendering the device inactive such as might be occasioned by sudden jolts or bumps to the individual car.

Still another object is the provision of means precluding the escape of air from the train line through the bleed line when the pressure is readmitted to the train line and the bleed valve is open.

Other objects reside in the provision of such a device which may be readily applied to an existing car, with a minimum of effort and difficulty, which will be reliable and efficient in operation, sturdy and durable in construction, and relatively simple and inexpensive to manufacture, assemble, and install.

Other objects reside in the combinations of elements, arrangements of parts, and features of construction, all as will be more fully pointed out hereinafter and disclosed in the accompanying drawings wherein there is shown a preferred embodiment of this inventive concept.

In the drawings wherein like reference num-

2

erals are utilized to designate like parts throughout the several views:

Figure 1 is a fragmentary side elevational view of one form of device embodying the instant invention as applied to a railway car including a train line and an air brake system including a conventional reservoir.

Figure 2 is a fragmentary top plan view of the mechanism disclosed in Figure 1, certain concealed parts thereof being indicated in dotted lines.

Figure 3 is a sectional view taken substantially along the line 3—3 of Figure 1 as viewed in the direction indicated by the arrow.

Figure 4 is a sectional view taken substantially along the line 4—4 of Figure 3 as viewed in the direction indicated by the arrows.

Figure 5 is a sectional view taken substantially along the line 5—5 of Figure 4 as viewed in the direction indicated by the arrows.

Figure 6 is a sectional view taken substantially along the line 6—6 of Figure 2 as viewed in the direction indicated by the arrows, certain parts thereof being broken away and certain other parts being omitted, and

Figure 7 is a longitudinal sectional view taken through the center line of a valve housing disclosed in Figure 1.

Referring now to the drawings, there is generally indicated at 10 a fragment of the frame of a railroad car, on which is mounted a train line 11, which leads through a valve housing 12, to be more fully described hereinafter to a line 13, which extends to the conventional triple valve. From the train line 11 a line 15 leads to a diaphragm housing 16 including a body portion 17 and heads 18 and 19. The diaphragm housing 16 is mounted on the frame 10 in a manner to be more fully described hereinafter. A portion 20 extending outwardly from the head 19 terminates in a flexible sealing member 21 of rubber or the like, through which extends a rod 22, provided with a pin 23 adapted to engage in a slotted aperture 24 carried by the operating lever 25 of a suitable sleeve valve 26, of conventional design positioned in a pipe 27 extending from the air reservoir 27a of the individual car. The extremity of the rod 22 extends beyond the pin 23 and terminates in a ball or similar weight 28, adapted to provide weight or impact to move the lever 25 when the rod 22 is actuated in the manner to be more fully described hereinafter.

Having reference now particularly to Figure 4 it will be seen that the diaphragm housing 16

includes a double concave partition which comprises the body 17, and that the heads 18 and 19 are arcuate in cross sectional configuration and concaved oppositely to the double concavities of the partition 17 to form chambers of elliptical cross sections 30 and 31, within which are positioned diaphragms 32 and 33, respectively. The diaphragms 32 and 33 are secured between the partitions and the head as by means of peripheral spaced bolts 34. Suitable ports 35 extend through a central point of the partition, and are closed as by a valve member 36, which comprises a resilient flap having an extension 37 secured as by screws 38 to the partition 17, and countersunk in a suitable recess within the chamber 31, to form a one-way valve whereby fluid may enter the chamber 31 but not leave the same therethrough.

A bore 39 extends upwardly from the chamber 31 into a recess 40 in a sleeve 41 threadedly engaged in the upper portion of the assembly 16, and a second bore 42 leads downwardly therefrom into a chamber 43 comprising the space between the diaphragm 32 and the partition 17.

In the normal operation of the device the chamber 30 is adapted to communicate with the air of the train line 11, and the diaphragm 32 held in the position shown in Figure 4 by the pressure of the train line. The chamber 31 is adapted to be fluid filled, with any suitable non-freezing fluid such as air or the like.

Referring back to the operating rod 22 the same extends through the sealing member 21, and a suitable bearing 45 threadedly engaged interiorly of the extending sleeve 20, and terminates in a head 46. A compression spring 47 positioned between the head 46 and the bearing 45 serves normally to bias the rod 22 inwardly toward the diaphragm 33, the arrangement being such that as long as the pressure in the train line is sufficiently great to hold the diaphragm 32 in the position shown, the diaphragm will force such fluid as remains in the chamber 43 through the ports 35 and the one-way valve 36 into the chamber 31, and force the diaphragm 33 outwardly, and hold the head 46 and hence the rod 22 in extended position, thus retaining the sleeve valve 26 in closed position. However, when the pressure in the train line drops to a point below the pressure exerted by the spring 47, which for example may be of 25 pounds, the pressure of the spring compresses the diaphragm 33 and forces the fluid in the chamber 31 through the ports 39 and 42 into the chamber 43, whereupon the pressure exerted by the spring serves to move the lever 25 to open the bleed valve. The size of the ports 39 and 42 is such that the opening of the valve is relatively slow, since the flow of the fluid in the chamber is restricted by the size of the ports, and the size of the ports may determine the effective time for opening the bleed valve after the pressure in the line has been exhausted.

It will now be seen that upon exhausting the pressure in the air line, the bleed valves of each car may be automatically opened in the manner above described, empty the reservoirs thereof. Under normal operating conditions the pressure of the train line remains in the neighborhood of 70 pounds, and in applying the brakes the pressure is reduced to approximately 35 pounds. Inasmuch as the pressure of 35 pounds is still 10 pounds in excess of the force exerted by the spring 47, it will be seen that in normal braking operation the diaphragms remain in the posi-

tion shown, and the bleed valve is not opened until the pressure is reduced abnormally or below the 25 pounds abovementioned.

Referring back to the recess 40 and the sleeve 41, a valve 50 is positioned therein and biased as by a spring 51, against a resilient valve seat 52, the valve seat being of sufficient strength normally to retain the valve in open position to permit passage of the fluid between the bores 39 and 42. A valve stem 53 extends upwardly through a closure member 54, and terminates in a transverse pin 55 which extends in the slot 56 carried by two oppositely disposed members 57. As best shown in Figure 1 the members 57 are pivotally secured as by pivots 58 to lugs 59 secured to the underside of an oil containing tank 60, about half full of oil, which is pivotally mounted as on a centrally disposed pivot 61 journaled in lugs 62 carried by the frame members 10.

The tank 60 comprises the means for rendering the device inoperative when the train is moving up or down an incline, and it will be seen that tilting of the tank in either direction effects through an associated member 57 pressure on the pin 55 to close the valve 50 and interrupt communication between the port 39 and 42, thus precluding the draining of fluid from one side of the device to the other such as might be occasioned by the inclination of the train. Means are provided for normally holding the tank 60 level, and comprise housings 65, containing as best shown in Figure 6 lugs 66 adapted to center relatively heavy compression springs 67. An annular groove or channel 68 about the center of the members 67 is closed by a resilient feelings member 69, adapted to keep dust and dirt out of the spring assembly, but of sufficient resiliency to expand with the contraction of air without in the device and hence not effect its operation. Thus it will be seen that the spring 67 serves normally to hold the tank 60 against rocking movement, and are of sufficient strength normally to align the tank with the frame 10 of the car. The tank 60, however, is filled with a viscous fluid such as oil, as indicated at 70, and the device tilts to close the valve 50 only when the oil has flowed from one end thereof to the other.

A chamber 71 is secured to the underside of the tank 60, and has secured therein as by means of peripherally spaced bolts 72 a flexible diaphragm 73. The diaphragm 73 is secured to a shaft 74 which in turn is secured as by means of a bolt 75 to one of the frame members 10, and the housing 71 communicates through a restricted port 76 with the tank 60. A resilient sealing gasket 77 is provided to surround the shaft 74. This device operates as a dashpot and hence serves to restrain oscillation or rocking of the tank, such as might be occasioned by jolting of the car, since the flow of oil through the restricted port is relatively slow, thus requiring the period of several seconds or minutes in accordance with the size of the ports to permit the oil to shift from one end of the tank to the other, and effect closing of the valve. Obviously a momentary jolt or rocking of the device would be of insufficient duration to permit or occasion such flow.

Means are also provided for manually closing the valve 50 as desired, and take the form of a transversely extending rod 80 secured at its midpoint to an arm 81 as by an extending bolt 82 and nuts 83, the opposite end of the arm 81 being secured to the valve stem 53. Each end of the

shaft 80 terminates in a collar 85 passed through a suitable aperture in external frame members 86 of the car body, and each collar having a longitudinally extending groove 87 therein terminating in radial grooves 88. A lug or pin 89 extends adjacent the collar 85, an operating handle 90 is secured to the outer extremity thereof. Thus it will be seen that when the handle 90 is given a quarter turn, the lug 89 becomes aligned with the transverse groove 87, and the device may be moved inwardly. This inward movement effects a closure of the valve 50, and a reverse quarter turn of the device will cause the lug 89 to engage in the outermost of the grooves 88 retaining the device as positioned. As best shown in Figure 1, suitable depending arms 91 are provided and have secured thereto springs 92, the opposite ends of which are secured to suitable points in the car body which serve normally to bias the arm 81 and the rod 80 toward latched position.

Means are correspondingly provided to preclude escape of air through the bleed valve after the reservoir has been emptied, and pressure is readmitted to the train line, and such means comprise the device 12 previously referred to. The construction 12 includes a chamber including a body portion 113 and a head 114, and a central partition 115 having two valves 116 and 117 positioned therein. A spring 118 surrounds the valve stem 119 of valve 117, and a spring 120 surrounds the valve stem 121 of valve 116. The arrangement is such that when the train line pressure exceeds 25 pounds, valve 117 is opened admitting air to the chamber 30, and thus closing the bleed valve. The parts are so proportioned that no air will pass from the train pipe to the car reservoir until a pressure sufficient to actuate the bleed device to closed position against spring 47 has been attained. Conversely, when the air is exhausted from the train line the air pressure from the triple valve passes back through the valve 116, and the pressure of the spring 120 being just sufficient normally to close the valve 116.

From the foregoing it will now be seen that there is herein provided an improved attachment for air brake systems or the like, which accomplishes all the objects of this invention, and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In an air brake control system including a train line and a car reservoir bleed valve, spring means biasing said bleed valve to open position, releasable manual means to maintain said bleed valve in closed position, diaphragm means in communication with said train line and associated with said spring means to oppose the latter and urge the bleed valve into a closed position when a predetermined pressure is maintained in said train line, said diaphragm means consisting of a housing having a central partition, diaphragm members on each side of said partition and forming chambers between the partition and the housing, means connecting the train line to the chamber formed between the housing and one diaphragm, the spring means extending into the chamber formed between the housing and the other diaphragm and abutting the latter, and one-way valve means controlling communication

through said partition, whereby the first mentioned diaphragm may transmit a pressure medium through the partition to bias the second diaphragm, and automatic and manual valve means in a by-pass communicating with the chambers on both sides of and contacting the partition.

2. In combination, a train line, a car reservoir bleed valve, a diaphragm chamber in communication with said line, an operating means for closing said bleed valve, resilient means opposing said operating means, a fluid connection communicating with said diaphragm chamber and said operating means and forming a fluid passage therebetween, and control means for effecting unrestricted flow from said diaphragm chamber to said operating means but restricting return flow to a predetermined rate.

3. In combination, a train line, a car reservoir bleed valve, a diaphragm chamber in communication with said line, an operating means for closing said bleed valve, resilient means opposing said operating means, a fluid connection communicating with said diaphragm and said operating means, and control means for effecting unrestricted flow from said diaphragm to said operating means but restricting return flow to a predetermined rate, said control means including a first passage having a non-return valve therein and a second passage having a flow-regulating valve therein.

4. In combination, a train line, a car reservoir bleed valve, a diaphragm chamber in communication with said line, an operating means for closing said bleed valve, resilient means opposing said operating means, a fluid connection communicating with said diaphragm chamber and said operating means, and control means for effecting unrestricted flow from said diaphragm to said operating means but restricting return flow to a predetermined rate, said control means including a first passage for effecting rapid non-return flow of pressure fluid from said diaphragm chamber to said operating means, and a second passage effecting a restricted return flow of fluid from said operating means to said diaphragm, said second passage including a flow-regulating valve and an adjustable control means for controlling said fluid regulating valve to adjust the rate of return flow through said second passage.

5. In combination, a train line, a car reservoir bleed valve, a diaphragm chamber in communication with said line, an operating means for closing said bleed valve, resilient means opposing said operating means, a fluid connection operatively associated with said diaphragm chamber and said operating means, and control means for effecting unrestricted flow from said diaphragm chamber to said operating means but restricting return flow to a predetermined rate, said control means including a first passage having a non-return valve therein and a second passage having a flow-regulating valve therein and manually operable means to close said flow-regulating valve.

6. The combination of claim 2 wherein said operating means includes a diaphragm responsive to a predetermined pressure in said diaphragm chamber.

7. In combination, a train line, a car reservoir bleed valve, a diaphragm chamber in communication with said line, a tubular guide projecting from said chamber, an operating rod controlling said bleed valve and including a piston mounted for reciprocating movement in said guide, a partition mounted in said chamber and dividing the

same into first and second compartments, an opening in said partition in communication with said compartments, first and second diaphragms mounted in said respective first and second compartments, valve means controlling the opening in said partition, and means normally urging said piston against said second diaphragm, said first mentioned diaphragm being responsive to a predetermined pressure in said line to force fluid in said first compartment through the opening in said partition, thereby flexing said second diaphragm and actuating said rod.

8. The combination of claim 7 wherein said means normally urging said piston against said second diaphragm includes a resilient member embracing said rod and positioned in said guide.

9. The combination of claim 7 wherein said valve means includes a concavo-convexed plate having an end portion fixed to said partition and disposed in said second compartment.

10. The combination of claim 7 wherein said chamber includes a pair of removable end plates having concaved inner faces, said partition having concaved faces opposing the inner faces of said end plates.

11. The combination of claim 7 and a return passage provided in said partition and communicating with said compartments, and a valve controlling said return passage.

12. The combination of claim 11 wherein said valve includes a movable plunger, means nor-

25 mally spacing said plunger from said return passage and counteracting said last-mentioned means for urging said plunger to a closed position for closing said return passage.

13. In combination, a train line, a car reservoir bleed valve, a housing including a pair of end walls, one end wall of said housing communicating with said train line for supplying a fluid into said housing, a partition in said housing 10 separating the same into a pair of compartments, a guide carried by the other end wall of said housing, an operating member for the bleed valve slidably supported by said guide, means mounted in one of said compartments for operating said member, and means mounted in the remaining of said compartments responsive to a predetermined pressure in said line for actuating said last-mentioned means.

ROBERT K. BIERY.
